(57) **CLAIM**

The ornamental design for a bottle, as shown and described.

DESCRIPTION

FIG. 1 is a perspective view of my new design;

FIG. 2 is a front elevation view of the design;

FIG. 3 is a rear elevation view of the design;

FIG. 4 is a right side elevation view of the design;

FIG. 5 is a left side elevation view of the design;

FIG. 6 is a top plan view of the design; and,

FIG. 7 is a bottom plan view of the design.

The broken lines of the top opening and bottom surface of the bottle show unclaimed subject matter only and form no part of the claimed design.
